[57] CLAIM

The ornamental design for paint spray fluid section repair tool, substantially as shown.

DESCRIPTION

FIGS. 1 and 2 are respectively left and right side views of a paint spray fluid section repair tool showing my new design.

FIGS. 3 and 4 show front and back views of the repair tool.

FIGS. 5 and 6 show respectively the top and bottom views and the wrenches and stops forming part of the overhead and base sections.
